UNITED STATES PATENT OFFICE

142,516

DESIGN FOR A PINOCHLE BOARD

Harold W. Eaton, Worcester, and Burt Trook,
Westboro, Mass.

Application June 14, 1945, Serial No. 120,107

Term of patent 14 years

(Cl. D34—5)

To all whom it may concern:

Be it known that we, Harold W. Eaton and Burt Trook, citizens of the United States of America, residing at Worcester and Westboro, respectively, in the county of Worcester and State of Massachusetts, have invented a certain new, original, and ornamental Design for a Pinochle Board, of which the following is a specification, reference being had to the accompanying drawing, forming a part thereof.

Fig. 1 is a plan view of a pinochle board, showing our design;

Fig. 2 is a side elevation thereof; and
Fig. 3 is an end elevation thereof.

We claim:

The ornamental design for a pinochle board, as shown.

HAROLD W. EATON.
BURT TROOK.
